UNITED STATES PATENT OFFICE.

PERRY L. SHEPARDSON, OF PITTSFIELD, MASSACHUSETTS.

FOLDING BED.

SPECIFICATION forming part of Letters Patent No. 389,018, dated September 4, 1888.

Application filed February 6, 1888. Serial No. 263,107. (No model.)

To all whom it may concern:

Be it known that I, PERRY L. SHEPARDSON, a citizen of the United States, residing at Pittsfield, in the county of Berkshire and State 5 of Massachusetts, have invented a new and useful Improvement in Folding Beds, of which the following is a specification.

My improvements relate more particularly to that class known as "cribs," and in which 10 sides and ends are required to retain infants upon the bed, and have for their object the provision of means for folding the bedstead, as well as the mattress or other bedding, together compactly; and my invention consists in the 15 combination and construction as hereinafter described, and more particularly pointed out in the claims.

My invention is fully illustrated in the accompanying drawings, in which Figure I is a 20 plan view of my improved bedstead. Fig. II is an end elevation of the frame in section on the dotted line $x x$ of Fig. I. Fig. III is an elevation in section of the frame on the dotted line $y y$ of Fig. I, and showing also a portion of the 25 bed-bottom. Fig. IV is a plan view of the device folded. Fig. V is an end elevation of the device in one stage of being folded, and Fig. VI is an end elevation in section through the frame on the dotted line $z z$ of Fig. IV.

B is the frame of folding crib and consisting 30 of the posts b at the four corners rising above the sides and ends and prolonged below them to supply the legs, the sides c , supplied at their inner sides and lower edges with 35 cleats d or other means for supporting the bed-bottom, and ends e , hinged to the posts b , and formed each in two sections united centrally by hinges to admit of their folding inward to permit the sides to approach. These 40 general features are old, and, together with a bottom in two sections hinged to the sides to drop down as the ends are folded, constitute the folding crib in general use; but heretofore it has not been practicable to use soft or spring 45 bed-bottoms with folding cribs, and it has been necessary to remove the mattress or bedding before folding the crib, to be restored only when the crib is unfolded for use, to obviate which disadvantages, by the use of a 50 woven or other flexible bed-bottom, and the provision of means for folding the bed-bottom

and mattress, or other bedding supported thereby, with the rest of the folding mechanism, is the object of the present improvements.

H is the frame of a bed bottom adapted to pass within the sides c of the frame B and rest upon the cleats d . The ends proper, h , of the bed-bottom have a space between them opposite the joints in the ends e , which space is 60 bridged by a bar, i , hinged at its ends at i' to the opposite ends h . The bar i lies upon the sides of ends h , and projections o from the ends h extend over the bar i inside of the hinges i' and bear upon it, so that the ends h are in effect rigid to resist weight applied from above, but have a double joint capable of being broken from below to leave the ends h as far removed as the distance between the joints i' .

From side to side of the frame H is stretched 70 a flexible web or membrane, I, care being taken not to let the end edges of said web extend over the ends h , which would be to tie them from swinging on the hinges i' .

Extending vertically upon the inner sides of 75 posts b , and to points above the highest extent of the ends e , and secured to said posts are four ways, g , (shown formed of stout wire,) and tied to these ways by eyes m , which are also hinges, is the frame H. The upper ends 80 of the ways g form stops, and the eyes m are loose enough upon the wire forming the ways to permit the ends h to be swung upon said ways as upon a hinge.

When from the extended position shown in 85 Fig. I it is desired to fold the crib, the bottom frame, H, with its mattress, is slid up upon the ways until stopped, as indicated in Fig. II, in a position clear above the ends e , a slight upward push is given ends h to throw 90 the hinges i' out of line, and the ends e are folded inward, as shown in Fig. V, to bring the bed-bottom and its mattress into the position shown in the same figure, from which position it is slid down upon the ways g to rest 95 upon the folded ends e , as shown in Figs. IV and VI.

Ample space is left between the sides c and the bed-bottom I for the mattress and bedding, and the folded frame H, when in the position 100 shown in Fig. VI, holds the rest of the parts firmly and compactly folded.

To prepare the folded crib for use, the bed-bottom is slid up to the position seen in Fig. V, when the act of straightening the ends *e* also brings the bed-bottom into position to be 5 slid to rest upon the cleats *d*.

Now, having described my invention, what I claim is—

1. The within-described improved combined folding bedstead and bed-bottom, consisting of posts *b*, sides *c*, inwardly-folding ends *e*, and means, as *d*, for supporting a bed-bottom, a bed-bottom consisting of a frame, *H*, adapted to have its sides rest within the sides *c*, a flexible bottom, *I*, and ends *h*, to one side 15 of the bottom *I*, and hinged, as shown and described, to form a joint, breaking upward to leave an interval between adjacent ends *h* as great as the thickness of the folded ends *e*, and ways in the posts *b*, having stops above the 2c ends *e*, combined with eyes in frame *H*, adapted

to follow upon said ways and form a hinge thereupon, all combined and operating as and for the purpose set forth.

2. In folding cribs, the combination, with 25 sides, corner posts, and inwardly-folding ends, of a bed-bottom consisting of a frame, *H*, adapted to rest within the crib-sides, a flexible bottom, *I*, stretched from side to side of frame *H*, ends *h* outside of the bottom *I* and having their corresponding ends separated by 30 a space, bars *i*, extending between adjacent ends *h* and hinged thereto, projections *o* from ends *h*, arranged to bear upon bars *i* between the hinges, ways *g* from posts *b*, and eyes holding the bed-bottom to the posts, all arranged 35 and operating as and for the purpose set forth.

PERRY L. SHEPARDSON.
